UNITED STATES PATENT OFFICE.

MILTON D. MORRILL, OF WASHINGTON, DISTRICT OF COLUMBIA.

SECTIONAL MOLD FOR CONCRETE CONSTRUCTION.

1,014,630.

Specification of Letters Patent.

Patented Jan. 9, 1912.

Application filed June 8, 1910. Serial No. 565,862.

To all whom it may concern:

Be it known that I, MILTON DANA MORRILL, a citizen of the United States, residing at Washington, in the District of Columbia, 5 have invented certain new and useful Improvements in Sectional Molds for Concrete Construction; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification. 15

My invention relates to concrete construction of buildings, in which reinforcing elements may be employed, and has reference more particularly to the elements employed 20 for molding the concrete and which may be designated as a sectional mold for concrete construction.

The invention has for its object to provide improved features of construction by which 25 sections of the mold are moved from one position to another as the construction of the wall progresses; also to provide improved features by which the sections of the mold are secured one to the other; also to provide 30 improved features in the formation and in the manner of securing in place spacing blocks or spools by which the sides of the mold are held in proper relation to each other; also in features of formation of the 35 spacing spools or block by which the spool or block is caused to hold in position reinforcing elements while at the same time properly spacing the sections of the mold one from the other; also in features of 40 construction of the mold by which may be facilitated the construction of the side walls together with the ceilings or floors of the concrete structure.

To the accomplishment of the foregoing 45 and such other objects as may hereinafter appear the invention consists in the features which will be hereinafter particularly described and then sought to be clearly defined by the claims, reference being had to the accompanying drawings forming a part hereof, and in which—

Figure 1 is a view showing in perspective a portion of the wall and a portion of the floor or ceiling, with the sectional members

of the mold and the spacing spools or blocks 5 and the reinforcing elements in relation to each other; Fig. 2 is a perspective, on an enlarged scale, of portions of the mold plates and a spacing spool or block, together with means for locking the several parts in 10 position; Fig. 3 is a perspective, on an enlarged scale, of a portion of two adjoining plates of the mold, showing the manner of locking them together, together with provisions for connection of the rod by which 15 one plate may be hinged to another plate for shifting the plates from one position to another in the progress of construction; Fig. 20 4 is a perspective view, with portions broken away, showing one of the rods for hinging 70 one plate to another; Fig. 5 is a perspective view of one of the mold plates for forming the inside corner of a wall; Fig. 6 is a perspective of one of the side plates of the mold; Fig. 7 is a perspective of one of the 75 side plates of the mold for forming the outside corner of the wall; Fig. 8 is a perspective of one of the bars for supporting the spacing spool or block in position, the bar being broken away. 80

In the drawings the numeral 1 designates metal side plates and 2 metal inside corner plates, while 3 indicates the metal outside corner plate of the sectional mold, which several plates are formed with out-turned 85 flanges 5 which are formed at suitable intervals with openings 6 for the passage of means for locking the plates together at desired points. The several plates at their corners are formed with a cut-away portion 7 90 so that at each corner where four of the plates come together there will be formed an opening for the passage of a bar 8 which will support in position a block or spool to space apart opposite sides of the mold, and 95 at such points the out-turned flanges 5 are cut-away on an incline as illustrated so as to afford easier access to the parts at such points. The plates constituting the side walls are spaced apart by blocks or spools 100 9 which are preferably made of concrete and are held in position by the bars 8 which pass through a central opening in the spool and are sustained by locking keys 10 to which are tapered or wedge shaped and 105 formed with a shoulder 11 to facilitate their withdrawal from the bars 8 and which bear against the flanges of the side plates as

illustrated. The bars 8 are formed with slots 12 at opposite ends for the reception of the locking keys 10, and these slots are preferably diagonally disposed so that the 5 keys will exert a strong drawing action when driven into place so as to more tightly draw and hold together the plates and the spacing spool to the plates. Each bar is also preferably formed at one end with an out-turned 10 lip 13 which will bear against the inside of the spool when the keys are driven into place so as to enable a better drawing action to be obtained by the keys, the opening in the spool for the passage of the bar A being 15 enlarged at the end where the lip 13 will enter the spool. The spool also serves as a support for the reinforcing elements which may consist of horizontally disposed metal rods 14 and vertically disposed metal rods 20 15, said rods being secured to the spools by tie rods 16 which will be either molded in the spools or threaded through openings molded therein and will have their outer ends bent over on to the rods 14 and 15 as 25 indicated in Figs. 1 and 2 of the drawing so as to secure the reinforcing rods thereto.

The meeting flanges of the wall plates of the mold at other points than where the spools are located thereto will be connected 30 together by U-shaped loops 16^a formed with shouldered or T-heads 17, the looped portion passing through openings in the flanges, and a tapering or wedge shaped key 18 driven through the loop so as to tightly 35 draw the flanges together so as to lock the plates in position. The wall plates of a lower section of the mold will be connected with the wall plates of an upper section by means of rods or bars 19 which will be pivotally connected at their ends to flanges of 40 the upper and lower tier or sections of the wall plates so that by such hinged connection when the lower portion of the wall has sufficiently set, a lower tier of plates may be 45 swung from their position into a higher position above an upper tier or section of the plates and brought into position so as to rest upon a tier or section of plates immediately next below, as for instance as illustrated in Fig. 1 of the drawing which shows one tier of plates in the operation of being 50 adjusted into position above a lower tier of plates upon which they will rest and to which they will be locked. In thus shifting one tier of plates from a lower to a higher position the tier of plates from which they have been unlocked and upon which they 55 will rest will not be disturbed in position for the reason that the upper and lower tiers of plates are locked together at the points where the spools are located by means of the keys 10 one of which lies above the flange of one tier of plates and the other beneath the flange of the lower tier of plates, so that

when the keys beneath the flanges of the 65 lower tier of plates are removed said plates will be left free to be elevated to the position illustrated in Fig. 1 without disturbing the tier of plates locked into position at the points of location of the spools by the keys 70 which bear against the top of the flanges to that tier of plates as will be obvious from an inspection of Fig. 1 of the drawing. It will thus be observed that the feature of locking the plates together by the keys bearing 75 against opposite bases of the flanges is an important feature for this purpose.

At the points where the bars or rods 19 are pivotally hinged to the flanges of the two tiers of wall plates, the locking means 80 for the plates consist of U-shaped loops 20 formed with shouldered or T-shaped heads 21 from one of which extends a lip or flange 22 to which the end of the rod or bar 19 will be connected by a pivot bolt 23. The 85 U-shaped portion of the loop 20 will pass through openings in the flanges of the wall plates and a wedge shaped key 24 will be passed through the same so as to lock the parts together and in position. 90

For the purpose of forming cove inside corners to the walls the inside corner plates of the mold are bent or curved in cross section as indicated in Figs. 1 and 5 of the drawing, and to form angular corners on 95 the outside of the wall the outer corner plates of the mold are angular as illustrated in Figs. 1 and 7 of the drawing. Said plates are otherwise formed and held in position like the other wall plates of the mold. For the purpose of forming cove lines where the walls and ceilings of the structure intersect with each other, bent or curved wall plates such as illustrated in Fig. 5 and designated by the numeral 2 are placed, and these 105 curved wall plates are secured by their flanges and keys to the flanges of the adjoining wall plates in the same manner as the vertically disposed wall plates secured one to the other. The wall plates of the 110 mold for forming the ceilings or floors are formed the same as the wall plates of the mold for forming vertical walls of the structure but such wall plates of the mold are disposed horizontally instead of vertically 115 as illustrated in Fig. 1 of the drawing, and these plates may or may not be connected together in tiers by hinged bars 19 as described. The spacing spools or blocks are disposed at the corners of the mold wall 120 plates same as in the molding of the vertical walls except that for the horizontal construction the spools will stand vertically instead of horizontally as illustrated in Fig. 1 of the drawing, and for the purpose of 125 affording temporary supports for the horizontally disposed wall plates of the mold wooden posts 25 are disposed at appropriate

points, for instance at the points where the vertically disposed spacing spools will occur so that said spools and the lower wall plates of the mold at such points will be temporarily supported by these posts. In such cases the bars 8 which pass through the spools may at their lower ends terminate within or on the level of the lower face of the spools so that the spools and plates may 10 rest squarely on the top of the posts 23. This is made possible by reason of the presence of the out-turned lip 13 to the bar 8 which as previously stated will bear against the inside of the spool. In molding the 15 horizontal or floor portion of the structure the upper side-walls of the mold are not applied until the concrete has been spread upon the lower wall plates of the mold. When that is done the upper plates of the mold are 20 spaced in position and by means of the wedge locking keys and the other elements of the lock previously described for the wall plates, said plates are drawn tightly into place so as to compress the concrete between 25 the wall plates of the mold. Reinforcing elements consisting of the lips 14 and 15 are applied and attached in the same manner as that described for the vertical walls except that they extend horizontally instead 30 of vertically, as illustrated in Fig. 1 of the drawing.

It will be observed that whether the sectional mold be employed for either the vertical or the horizontally disposed walls of 35 the structure, the construction of the parts of the molds are the same and their mode of application practically the same, the one difference being in the horizontal or vertical disposition of the side wall plates of the 40 mold.

By constructing and applying the parts as described I provide a very simple construction which possesses strength in its several parts and which is capable of application with ease and expedition, and make it 45 possible to readily shift the wall plates of the same from one position to another in the progress of the construction.

I have described with particularity the 50 preferred details of construction and arrangement of the several parts but it is obvious that changes can be made in specific details of the several parts without departing from the spirit of the invention and 55 from its scope as expressed in the appended claims.

Having described my invention and set forth its merits what I claim is:

1. A sectional mold for concrete construction comprising flanged metallic wall-plates 60 recessed at the corners of adjoining plates, spacing cores or spools interposed between opposite wall-plates, removable slotted supports extending from the ends of the spac-

ing spools and lying in the recesses of adjoining wall-plates, and locking keys passing through the slotted supports of the spacing spools and bearing against flanges of the wall-plates. 65

2. A sectional mold for concrete construction 70 comprising flanged metallic wall-plates recessed at the corners of adjoining plates, spacing cores or spools interposed between opposite wall-plates, removable slotted supports extending from the ends of the spacing spools and lying in the recesses of adjoining wall-plates, and locking keys passing through the slotted supports of the spacing spools, one key bearing against a flange of one plate and another against a 75 flange of an adjoining plate to enable one set of plates to be removed without unlocking the other set of plates. 80

3. A sectional mold for concrete wall construction, comprising removable side-walls, 85 and means hinging the sections of wall together to permit one section to be swung from one position to another in relation to an adjoining section in progressive extension of the mold. 90

4. A sectional mold for concrete construction comprising flanged metallic wall-plates, arranged in rows, means for locking the plates together, and bars pivotally connected at one end with wall-plates of one of 95 said rows and at the other end with the wall-plates of another row for transferring the plates of one row to a position in advance of the plates of another row. 100

5. A sectional mold for concrete construction comprising flanged wall-plates arranged in rows, means for locking the plates together, and bars pivotally connected at one end with plate locking means of one row of plates, and at the other end 105 with plate locking means of an adjoining row of plates for transferring the plates of one row to a position in advance of the plates of another row. 110

6. A sectional mold for concrete construction comprising flanged wall-plates arranged in rows, U-shaped members passed through flanges of the wall-plates and formed with shoulders to bear against the flange of one plate, and with a flange, locking keys passed through the loops of said U-shaped member and bearing against the oppositely disposed flanges of the adjoining plates, and bars pivotally connected at one end to the flanges of the U-shaped members 115 of one row of plates and at the other end to the flanges of the U-shaped members of another row of plates for transferring the plates of one row to a position in advance of the plates of another row. 120

7. A sectional mold for concrete construction comprising flanged metallic wall plates, spacing spools or cores interposed be-

tween opposite wall-plates, slotted supports
extended through the spacing spools and
formed each with a laterally extending lip
bearing against a shoulder within the spool,
5 and locking keys passed through the slotted
portion of the supports and bearing against
flatges of the wall-plates.

In testimony whereof I affix my signature
in presence of two witnesses.
